UNITED STATES PATENT OFFICE.

JOHN E. MITCHELL AND ORVILLE MITCHELL, OF ST. LOUIS, MISSOURI.

DRIVING MECHANISM.

Application filed October 23, 1926. Serial No. 143,550.

This invention relates to novel feed mechanism for use, particularly, in cotton cleaning machines of the type illustrated in various patents heretofore granted to John E. Mitchell, one of the joint inventors herein, and as to a later form of such machine, in a pending application of the said John E. Mitchell, Serial No. 102,609, filed April 17th, 1926.

The general object of the invention is to provide feed mechanism which shall operate in a continuous manner, as distinguished from an intermittent feeding operation which has characterized all prior machines of the type referred to. Such intermittent feed mechanism is also illustrated in various prior patents, for example, in the patent to Mitchell & Parks, No. 1,360,132, dated November 23rd, 1920.

An intermittently operating feeding mechanism has the disadvantage that the cotton is fed in relatively large bunches to the saw cylinder, which results in the saw cylinder being overloaded at one time and insufficiently supplied with cotton in the interval between the feeding operations. This disadvantage is heightened by the fact that the cotton is not uniform in its compactness, so that less cotton is fed in one feeding cycle of the rollers than at another.

The present invention aims to overcome the objections incident to an intermittent feeding operation by providing for a continuous movement of the feed rollers, but by such means as will prevent damage to any of the operating parts due to the feed rollers being stopped by the introduction between them of a stone, piece of metal, or the like.

The present invention also provides means for readily adjusting the speed of rotation of the feed rollers by a simple shifting of the drive belt from one sized pulley to the other without, in any manner, changing the relation of the other parts of the mechanism.

With the above objects in view, the invention is characterized by the provision of a yieldingly mounted pulley carrying a pinion for driving the feed rollers and driven by a belt from a pulley on the drive shaft, the pinion being so mounted that in the event the feed rollers are suddenly stopped by a stone, or the like, the pinion will be caused to travel downward on the gear it is driving and thereby carry downward the pulley on which it is secured, which operates to cause the belt to loosen and move away from the drive pulley

on the drive shaft and thus stop the drive of the feeding mechanism.

The invention is further characterized by the provision of a cone pulley, or a series of pulleys of different sizes operating as a unit, which are keyed to move with and slide on the drive shaft so that the drive belt may be readily placed on one or the other of these pulleys to vary the speed at which the feed rollers are rotated.

The invention is still further characterized by the provision of means for insuring that the drive belt shall be caused to clear its driving pulley when the driven pulley operated thereby is lowered by the stoppage of the feed rollers.

The invention is still further characterized by means for holding the driving mechanism in the inoperative position after the accidental stoppage of the feed rollers, so that the feed mechanism will not again be operated until the obstruction has been removed and the operator has released the holding mechanism. This device also permits the feed to be discontinued at any time at the will of the operator.

The specific embodiment of the invention illustrated in the accompanying drawing comprises a pair of feed rollers geared together, a driving gear for driving said rollers, a swinging arm hinged on the shaft of said gear, a pulley with an attached pinion carried on one end of the swinging arm so that, regardless of the position of the arm, the pinion is always in mesh with the driving gear, and a spring or weight on the opposite end of the swinging arm for maintaining a yielding tension on the belt which drives said pulley.

An additional advantage of this construction is that the swinging arm automatically adjusts the tension on the belt either due to its various positions on the pulleys or to stretching of the belt, in addition to permitting movement of the driven pulley so as to permit the belt to slacken and stop the feeding mechanism.

The invention is illustrated in the accompanying drawing, in which—

Figure 1 is a view in side elevation of a cotton cleaning machine provided with our improved feeding mechanism;

Figure 2 is a similar view looking from the opposite side of the machine to that shown in Figure 1;

Figure 3 is a broken sectional view through

the upper portion of the machine viewed in the direction of Figure 2; and

Figure 4 is a broken view partly in section showing the catch for the rod that holds the feed mechanism in an inoperative position, and the arrangement of the adjustable series of pulleys on the drive shaft.

Referring now to the drawing, the numeral 1 indicates the casing of the machine in which the operating mechanism (not shown) for cleaning cotton is enclosed and in the side walls of which are mounted in suitable bearings the shafts of the various rotating elements constituting said cleaning mechanism. 15 As the construction and arrangement of such cotton cleaning mechanism is not involved in the present application, and, moreover, is disclosed in one form or another in various prior patents, and especially in the pending application above referred to, no illustration of such mechanism is deemed necessary.

The upper part of the casing 1 provides a relatively narrow portion, indicated by the numeral 2 in Figure 3, through which the cotton is fed to the cotton cleaning mechanism below. Mounted in this upper portion 2 of the casing are two feed rollers 3 and 4. The feed roller 3 is mounted on a shaft 5 having bearings in the side walls of the casing, as above stated, and on one end of this shaft is loosely mounted a gear 6 secured on the inner side of which is a pinion 7. The feed roller 4 is, in like manner, mounted on a shaft 8 on one end of which is secured a gear 9 which is in mesh with the pinion 7. The end of the shaft 5 projects beyond the gear 6, and pivotally mounted intermediate its ends on this projecting end of the shaft is an arm 10 to the outer end of which, the left-hand end shown in Figure 1, is secured one end of a coil spring 11, the other or lower end of which is fixedly secured to the casing, as indicated at 12. Rotatably mounted in the arm 10 near its opposite end is a stub shaft 13 on the outer end of which is secured a pulley 14 and on the inner end of which is secured a pinion 15 (Fig. 3) which is in mesh with the gear 6. The pulley 14 is driven by a belt 16 which, at its upper end, passes over said pulley, and at its lower end passes over one or the other of the pulleys 17, 18, 19 (Figs. 1 and 4). These pulleys are formed as a unitary structure and their hub or barrel is slidably mounted on the drive shaft 20 through the medium of a key 21. In changing the belt 16 from one pulley to the other to vary the speed of rotation of the feed rollers, the pulleys are simply slid in one direction or the other on the shaft 20 to bring the pulley selected in line with the pulley 14. The key 21, of course, maintains the pulleys in fixed rotational relation with the shaft 20. As shown by Figure 2, each of the shafts 5 and 8 is provided at its end opposite to that shown in Figure 1, with a gear 22, which gears intermesh and which are for the

purpose of providing a uniform distribution of power to the feed rollers 3 and 4. When the pulley 14 is rotated, the pinion 15 causes the gear 6 to rotate which, in turn, through the medium of the pinion 7, rotates the gear 9. This gear rotates the feed roller 4 and the shaft 8 which, in turn, rotates the gear 22 at the opposite end of shaft 8, which gear rotates the companion gear 22 on the corresponding end of the shaft 5, which thereby causes the feed roller 3 to be rotated.

The main saw cylinder (not shown) is mounted on the shaft 20. The numeral 23 indicates the main drive pulley which is mounted on one end of a shaft 24, and which pulley is driven by a belt (not shown) from any suitable source of power. On the opposite end of the shaft 24 to that shown in Figure 1, there is mounted a pulley 25, and similar pulleys indicated, as to each, by the numeral 26, are mounted on the corresponding ends of the shafts of the various rotating members constituting the cotton cleaning mechanism, all of these pulleys being driven by a belt 27. One of the shafts driven by a pulley 26, that at the lower lefthand corner of Figure 1 and the lower righthand corner of Figure 2 and indicated by the numeral 28, is provided at the end shown in Figure 1 with a gear 29 which is in mesh with a gear 30 which, in turn, is in mesh with a gear 31 (Fig. 1), secured near the end of the shaft 20 containing the pulleys 17, 18 and 19. Through the driving connections described, the shaft 20 and the pulleys thereon are rotated and, of course, the cleaning mechanism within the casing, operated. The pulley 14 is rotated by the belt 16 in the direction indicated by the arrows, and it will now be seen that if the feed rollers 3 and 4 should be prevented from rotation by the entrance of a stone, piece of metal, or the like, between them, as the gears 6 and 9 cannot rotate, the pinion 15 will be caused to travel downward over the periphery of the gear 6, causing the inner end of the arm 10 to be lowered against the resistance of the spring 11, and correspondingly lowering the pulley 14. This movement, of course, causes the lower end of the belt 16 to drop below the pulley 17, 18 or 19, over which it was running at the time, and thus interrupt the driving connection between the shaft 20 and the pulley 14, so that the pulley 14 and pinion 15 will no longer be rotated. However, it has been found that a very slight contact of the belt 16 with one or the other of the pulleys 17, 18, 19, is sufficient to exert considerable driving power on the pulley 14, and in order to insure that when the pulley 14 is lowered, the lower end of the belt 16 will entirely clear the pulleys, or the pulley on which it is running at the time, we mount on the side of the casing a rod 32 which projects laterally outward a short distance from the side of the belt 16, so that when the pulley 14

is lowered by the arm 10 in the manner previously described, the belt will engage the rod 32 and cause it to be moved out of contact with the pulley 17, 18 or 19 on the pulling side thereof and thus cause the belt to entirely clear the pulley, at least as to such side, and prevent any tendency of the belt by contact with the drive pulley, to rotate the pulley 14.

In order to permit the operator to render the feed rollers inoperative at will, or to hold the feed mechanism in inoperative position while removing an obstacle from the rollers, we pivotally mount on the inner end of the arm 10, the upper end of a rod 33 which, at its lower end, is bent at right angles as indicated at 34 in Figure 4 so that it can be pressed downward by the operator, and at some distance from its lower end, has secured thereon a collar 35. The lower portion of the rod 33 beyond the collar 35 rests in a slot 36 provided in the outer end of a bracket 37 (Fig. 4) secured on the side of the casing. By drawing down the rod 33 a sufficient distance, the inner end of the arm 10 will be lowered to release the belt 16 from engagement with one of the drive pulleys 17, 18, 19 and thus stop the feed of the machine. By removing the lower end of the rod 33 from the slot 36 and depressing said rod until the collar has passed below the bracket 37, and then inserting the rod above said collar in the slot 36, the inner end of the arm 10 may be held in the lowered position to maintain the feed mechanism in an inoperative position for such length of time as may be desired.

While we have shown our improved feed mechanism as applied to a cotton cleaning machine, it will be obvious that it is not limited to such application, but would be equally applicable for use in any character of machine where material is passed between two positively driven rotating members and where the accidental entrance between said members of some object of a sufficient size or degree of hardness to cause stoppage of such members, might cause damage to the machine. With our improvement, it will be seen that while the feed rollers or other rotating members are positively and continuously driven and at any desired speed of rotation, nevertheless the sudden blocking of rotation of the feed rollers or other rotary members will not cause injury, for the reason that the driving pinion 15 immediately rides over the periphery of the gear which it is driving, that indicated by 6 in the drawing, and causes the driving belt to be separated from its driving pulley, and thus prevents further rotation of the pulley 14 which drives said pinion.

It will be further seen that by mounting the driving mechanism in the manner described and illustrated herein, the pinion 15 will be maintained in mesh with the gear 6 in any position of the arm 10, and the belt 16 will be maintained under tension in any ad-

justment thereof on the pulleys 17, 18, or 19.

We claim:

1. In mechanism of the class described, a gear, a pinion in mesh with said gear for rotating the same, and orbitally movable over the periphery thereof, yieldable means tending normally to resist orbital movement of said pinion in one direction, a pulley fast with said pinion for driving the same and bodily movable therewith, and a belt drive for said pulley maintained under tension by said yieldable means.

2. In mechanism of the class described, a gear, an arm pivotally mounted intermediate its ends in line with the axis of said gear, a pinion carried toward one end of said arm in mesh with said gear, a pulley fast with said pinion for driving the same to rotate said gear, a belt drive for said pulley, and means exerting yielding pressure on the other end of said arm and normally maintaining said belt under tension.

3. In combination, a pair of rotary members mounted in geared relation, a driving gear secured on the shaft of one of said members, an arm pivotally mounted intermediate its ends in line with the axis of said driving gear, a pinion for driving said gear mounted toward one end of said arm, a pulley fast with said pinion for driving the same, a belt drive for said pulley, and means for exerting yielding pressure on the other end of said arm for holding the belt of said drive normally under tension.

4. In combination with a pair of rotary members mounted in geared relation, a driving gear mounted on the shaft of one of said members, an arm pivotally mounted intermediate its ends on the shaft of said gear, a pinion for driving said gear mounted near one end of said arm, a driven pulley fast with said pinion for driving the same, a driving pulley located below said driven pulley, a belt connecting the two pulleys, and means for exerting yielding pressure on the other end of said arm for holding the belt of said drive normally under tension, the arrangement being such that upon accidental stoppage of said rotary members, said pinion will be caused to ride over the periphery of said driving gear to cause the end of said arm carrying said pinion and said driven pulley to be lowered, whereby to separate said belt from its driving pulley.

5. In mechanism of the class described, a gear, an arm pivotally mounted intermediate its ends in line with the axis of said gear, a pinion carried toward one end of said arm in mesh with said gear, a pulley fast with said pinion for driving the same to rotate said gear, a belt drive for said pulley including a second pulley for driving said belt, means exerting yielding pressure on the other end of said arm and normally maintaining said belt under tension, the arrangement being

such that upon accidental stoppage of said gear, said pinion will be caused to ride over the periphery of said driving gear to cause the end of said arm carrying said pinion and said pulley to be lowered, whereby to loosen said belt on said second or driving pulley, and means positioned in proximity to said belt and adapted to be engaged thereby as said pulley is lowered to cause said belt to be moved out of driving engagement with said second pulley.

6. In mechanism of the class described, a gear, an arm pivotally mounted intermediate its ends in line with the axis of said gear, a pinion carried toward one end of said arm in mesh with said gear, a pulley fast with said pinion for driving the same to rotate said gear, a belt drive for said pulley including a driving pulley for said belt, means exerting yielding pressure on the other end of said arm and normally maintaining said belt under tension, and means associated with the first end of said arm for holding such end in a lowered position, whereby to release the tension on said belt and maintain the same clear of its driving pulley.

7. In mechanism of the class described, a gear, a pinion in mesh with said gear for rotating the same, and orbitally movable over the periphery thereof, yieldable means tending normally to resist orbital movement of said pinion in one direction, a pulley fast with said pinion for driving the same and bodily movable therewith, a belt drive for

said pulley maintained under tension by said yieldable means, and means for varying the speed of said belt drive.

8. In mechanism of the class described, a gear, a pinion in mesh with said gear for rotating the same, and orbitally movable over the periphery thereof, yieldable means tending normally to resist orbital movement of said pinion in one direction, a pulley fast with said pinion for driving the same and bodily movable therewith, a belt drive for said pulley maintained under tension by said yieldable means, and adjustable means for varying the speed of said belt drive.

9. In mechanism of the class described, a gear, a pinion in mesh with said gear for rotating the same, and orbitally movable over the periphery thereof, yieldable means tending normally to resist orbital movement of said pinion in one direction, a pulley fast with said pinion for driving the same and bodily movable therewith, a drive shaft, a series of pulleys of different sizes slidably mounted on said drive shaft to be driven thereby, and a belt passed over said pulley and one or the other of said series of pulleys, the latter being slidable on the drive shaft to bring one or the other of them into line with said first named pulley, whereby to vary the speed of the drive.

In testimony whereof, we have hereunto set our hands.

JOHN E. MITCHELL.
ORVILLE MITCHELL.
